US0D1033134S

(12) **United States Design Patent** (10) **Patent No.:** **US D1,033,134 S**
(45) **Date of Patent:** **** Jul. 2, 2024**

(54) **BLADE FOR A MICRO PUREE MACHINE**

(71) Applicant: **SharkNinja Operating LLC**,
Needham, MA (US)

(72) Inventors: **Lukas Tubby**, London (GB); **Sam Bannister**, London (GB); **Helen Williams**, Needham, MA (US)

(73) Assignee: **SHARKNINJA OPERATING LLC**,
Needham, MA (US)

(**) Term: **15 Years**

(21) Appl. No.: **29/845,156**

(22) Filed: **Jul. 5, 2022**

(51) **LOC (14) Cl. 31-00**

(52) **U.S. Cl.**

(57) **CLAIM**

The ornamental design for a blade for a micro puree machine, as shown and described.

DESCRIPTION

FIG. 1 is a top, front and right side perspective view of the blade for a micro puree machine, embodying our new design;

FIG. 2 is a front elevation view thereof;

FIG. 3 is a rear elevation view thereof;

FIG. 4 is a left side elevation view thereof;

FIG. 5 is a top plan view thereof;

FIG. 6 is a right side elevation view thereof; and,

FIG. 7 is a bottom plan view thereof.

1 Claim, 2 Drawing Sheets
